DESIGN FOR A BRAKE LEVER

Ray A. Sandberg, Waukegan, Ill., assignor to
Houdaille-Hershey Corporation, Detroit, Mich.,
a corporation of Michigan

Application October 17, 1938, Serial No. 80,484

Term of patent 7 years

To all whom it may concern:

Be it known that I, Ray A. Sandberg, a citizen of the United States and a resident of the city of Waukegan, in the county of Lake and State of Illinois, have invented a new, original and ornamental Design for a Brake Lever, of which the following is a specification, reference being had to the accompanying drawing forming a part thereof.

On the drawing:

Figure 1 is a side elevational view of the brake lever showing my new design.

Figure 2 is a front elevational view thereof.

The characteristic features of the design reside in a brake lever having a knee portion and a palm grip portion of the configurations disclosed and having the relationship of the palm grip portion to the knee portion as disclosed.

I claim:

The ornamental design for a brake lever, as shown and described.

RAY A. SANDBERG.
